Inventor:

Eliel L. Sharpneck

By Henry J. Miller, Atty.

UNITED STATES PATENT OFFICE.

ELIEL L. SHARPNECK, OF WINTHROP, MASSACHUSETTS, ASSIGNOR OF ONE-HALF TO HIMSELF, AND ONE-HALF TO FREDERICK W. MILLAY, OF HAVERHILL, MASSACHUSETTS.

HEEL FOR SHOES.

1,259,917.

Specification of Letters Patent. Patented Mar. 19, 1918.

Application filed August 8, 1916. Serial No. 113,813.

To all whom it may concern:

Be it known that I, ELIEL L. SHARPNECK, a citizen of the United States, residing at Winthrop, in the county of Suffolk and State of Massachusetts, have invented new and useful Improvements in Heels for Shoes, of which the following is a specification, reference being had to the accompanying drawings, forming part thereof.

10 This invention has reference to improvements in heels for shoes and particularly to such heels having seats to receive the heel portions of the shoe soles.

One object of the invention is to provide 15 a shoe heel having a seat to receive the sole in which the wall of said seat is constituted by a casing member coextensive with the heel and adapted to be enameled or coated with finishing or coloring material.

20 Another object of the invention is to provide a heel constituted by a casing and a filler in which the shape of said casing and filler tends to retain the casing on the filler.

Other objects of the invention will appear 25 from the following description.

The invention consists in the heel comprising the filler member and the casing member extending as a wall above the filler member to provide a seat for the sole, which 30 wall is adapted to meet the upper to afford a neat and inconspicuous finish.

The invention also consists in the complementary shape of the casing and the filler whereby the tendency of the casing is to hug 35 the filler.

The invention also consists in such other novel features of construction and combination of parts as shall hereinafter be more fully described and pointed out in the 40 claims.

Figure 1, represents a perspective view of the improved heel.

Fig. 2, represents a similar view of a modified form of the same.

45 Fig. 3, represents a sectional view taken on line 3—3 Fig. 1.

Fig. 4, represents a similar view taken on line 4—4 Fig. 2.

Fig. 5, represents a plan view of Fig. 2.

50 Fig. 6, represents a vertical sectional view taken on line 6—6 Fig. 5, the heel lift being omitted.

Fig. 7, represents a bottom plan view of Fig. 6.

Similar characters of reference designate 55 corresponding parts throughout.

As shown in the drawings the casing members A and B are in all cases approximately of similar shape having the upper curved wall or edge 7 and tapering downward from 60 said wall or edge 7 following approximately the inward back curve 8 and front curve 9 to the bottom of the heel or to the point adapted to receive the heel lift 10. These 65 inward opposed curves 8 and 9 contract the diameter of the casing from front to back, as on line 6—6 Fig. 5 and the sides 11, 11 of the casing are curved slightly inward all of said curves resisting outward pressure.

The casing members A and B preferably 70 are made of sheet metal or sheet material and their curved elements 9, 9 are inturned from the sides 11, 11 and are furnished with bent edges which are adapted to be received in suitable recesses of the filler block or substance C or D as the case may be. In the form shown in Figs. 1 and 2, the inturned 75 curved elements 9, 9 have their edges bent inward and folded together to form the rib 12 which follows the curve of the elements 80 9, 9 and the filler block C has the groove c to receive said rib 12.

In the form shown in Figs. 2, 4, 5 and 6 of the drawings the curved casing elements 9, 9 have their edges 13, 13 turned inward 85 without being folded together or engaged and the upper and lower portions of said elements 9, 9 are furnished with the bent lips 14, 14 and 15, 15 which overlap the corresponding ends of the filler block D while 90 said edges 13, 13 are received by the groove d of said block D.

The filler blocks C and D preferably are 95 made of wood or other suitable material and should preferably be of a size and shape approximately to be received by their respective casings A or B and to be secured therein by suitable cement. In some cases I may however prefer to construct the filler blocks C or D of plastic material molded into shape 100 prior to their insertion in said casings or molded in said casings.

The casings A and B may be of metal or material adapted readily to receive and retain a finish of enamel or color which is unbroken by any joint or seam on the exposed surface of the heel. The upper surfaces of the filler blocks are adapted to receive the 105

heel portions of the shoe soles to which these improved heels are applied and such heel portions of the soles are embraced by the walls 7 of the casings which walls 7 fit snugly against the adjacent portions of the shoe.

Having thus described my invention I claim as new and desire to secure by Letters Patent:

- 10 1. A heel comprising a casing and a filler for said casing, said casing being coextensive with said filler and having meeting edges bent inward to constitute a rib which rib is received by the filler.

2. A heel comprising a casing and a filler 15 for said casing, said casing being coextensive with said filler and having meeting edges bent inward and engaged with said filler.

3. A heel comprising a casing and a filler 20 for said casing, said casing being coextensive with said filler and having a vertically curved front constituted by elements having meeting edges inturned from said elements and following the curves thereof, said filler 25 having a groove to receive said meeting edges.

ELIEL L. SHARPNECK.
